F. B. SPROSS

SELF SERVING DEVICE

Filed Jan. 24, 1923

UNITED STATES PATENT OFFICE.

FREDERICK B. SPROSS, OF BERGEN, NEW YORK.

SELF-SERVING DEVICE.

Application filed January 24, 1923. Serial No. 614,562.

To all whom it may concern:

Be it known that I, FREDERICK B. SPROSS, a citizen of the United States, residing at Bergen, in the county of Genesee and State of New York, have invented certain new and useful Improvements in Self-Serving Devices, of which the following is a specification.

The object of this invention is to provide a self serving device that is adapted to be placed on a table so that all of the eatables and dishes placed thereon can be reached by any person desiring it without the help of his neighbor.

These and other objects of this invention will be fully illustrated in the drawing, described in the specification and pointed out in the claim at the end thereof.

In the accompanying drawing:

Figure 1 illustrates the self serving device as it will appear when placed on a table, the table cover supported by the device being partly unfolded to cover a portion of the table.

Figure 2 is a horizontal sectional view of the self serving device, the section being taken on the line 2^x—2^x of Figure 1 looking at it in the direction of the arrow.

Figure 3 is a detail sectional view of the table cover support of the device.

Figure 4 is an enlarged detail sectional view of the central portion of the support of the self serving device, the section being taken on the line 4^x—4^x of Figure 1.

Figure 5 is an enlarged bottom plan view of the central portion of the table cover support of the device.

In the several figures of the drawing like reference numerals indicate like parts.

The self serving device forming the subject matter of my present invention is intended to be used on a dining table and with it all of the persons sitting at the table are able to serve themselves with all of the eatables placed on the device without the help of others.

As illustrated in the figures of the drawing this is accomplished by means of a turntable 1. This turn table has a central hub 2 in the form of a sleeve mounted centrally on the under side thereof. The hub in turn is mounted to rotate on a central standard or pivot member 3 supported by the base 4. This base is formed by a socket 5 that is supported by a series of four legs 5, 5 which help to give the device a firm and

stable support for the turntable 1 to rotate thereon. Formed on the free ends of the hub 2 and the hub 4 are suitable ball races between which a series of balls 6, 6 are placed to form a ball bearing between the turntable and its stationary support on which the turntable can easily rotate. Braces 7, 7 are mounted to the end of the hub 2 and extend radially from it to the under side of the turntable to increase the supporting strength thereof.

Mounted on the under side of the turntable is a series of four radial extension members 8, 8. These extension members are adapted to slide in and out between the guides 9, 9 and serve to support an extension ring 10. By adding this ring to the turntable the area thereof is materially increased. The ring is, therefore, used when it is necessary to place more dishes on the turntable than can be accommodated by the turntable without this extension. Four segmental strips 11, 11 are fastened to the under side of the extension ring 10 and the extension members 8, 8 are adapted to project between the spaces of these segmental strips. Suitable shoulders are thus formed on either side of the extension members 8 so that when the extension ring is taken hold of and turned the turntable 1 is turned with it.

The central standard or pivot member 3 is extended by the hollow tubing 3^A that projects through the center of the turntable and has the arms 12, 12 pivoted on the upper end thereof. For this purpose the upper end of the hollow tubing is split into four sections that are bent outwardly to form supports for the supporting plate 13. The supporting plate 13 is fastened to the outwardly bent flanges of the standard 3^A by means of the rivets 14. These rivets pass through the plate 13 into the out turned flanges and are then bent up in a loop around a ring 15 and back against the supporting plate. In this way the supporting plate 13, the end of the standard 3^A and the ring 15 are clamped together with each of the rivets 14.

The supporting plate 13 is perforated between the out turned flanges of the standard 3^A so that one of the arms 12 can pass through each of the openings provided therein. These arms are mounted to swing on the ring 15 and for this purpose each of the arms has an eye 16 formed on the end

thereof through which the ring is adapted to project to form a pivot for the arm. Each of the arms 12 has a brace 17 fastened thereto. This brace normally rests 5 on top of the supporting plate 13 as illustrated in Figure 3 and holds the arm 12 in a vertical position. When it is desired to make the arms 12 extend horizontally over the self serving device and over the 10 table the free ends of the braces 17 are pulled away from the supporting plate so that the arms can drop down into the horizontal position illustrated at the right in Figure 1. In this latter position the arms 15 12 project over the table and are adapted to support a suitable table cover 18 over the self serving device and the table surrounding it to prevent flies or dust from getting to the food placed on the self serving device.

20 When the self serving device is in use the cover 18 and its supporting arms 12, 12 are folded up into the vertical position illustrated at the left in Figure 1 and a suitable ribbon or other fastening means 25 may be placed around the cover and its arms when in this position to give it a neat appearance.

30 The self serving device is to be placed on a table or portion of a table where a number of persons are being served. All of the eatables except the individual dishes can then be placed on the turntable of the

device and each person in turn can rotate the turntable until the particular dish wanted is opposite him within easy reach 35 that will enable the person to help himself without assistance from his neighbors.

I claim:

In a self serving device, the combination of a base, a standard supported by 40 said base, a turntable mounted to rotate on said standard, a thrust bearing interposed between said turntable and said base, extension members mounted to slide radially on the under side of said turntable, an extension ring adapted to rest on said extension members, shoulders formed on the under side of said extension ring, said extension member being adapted to engage 45 between said shoulders, a supporting platform mounted on the upper end of said standard, a series of radial arms mounted to swing on said platform, a brace for each of said arms, said braces being adapted to rest on top of said platform to hold said 50 arms in a vertical position, said braces also being adapted to be disengaged from said platform to allow said arms to rest on said platform in a horizontal position, a table 55 cover adapted to be supported by said arms. 60

In testimony whereof I affix my signature.

FREDERICK B. SPROSS.
